[57] CLAIM

The ornamental design for a merchandising display unit, as shown and described.

DESCRIPTION

FIG. 1 is a front, top, and right side perspective view of the merchandising display unit of the present invention.

FIG. 2 is a front elevational view thereof;

FIG. 3 is a right side elevational view thereof, the left side elevational view being a mirror image.

FIG. 4 is a top plan view thereof;

FIG. 5 is a bottom plan view thereof; and,

FIG. 6 is a rear elevational view.
